HAND LIFT TRUCK

George Quayle, Philadelphia, Pa., assignor to The
Yale & Towne Manufacturing Company, Stamford,
Conn., a corporation of Connecticut

Application May 19, 1939, Serial No. 274,659

28 Claims. (Cl. 254—10)

This invention relates to a lift truck of the type in which an elevating platform is elevated relatively to a main frame through actuation of a hand operated lifting mechanism.

5 More particularly, my invention relates to a truck in which the lifting mechanism is of the multi-stroke type; that is, in which the lifting handle through a series of swinging movements, elevates the load platform. Trucks of the type to 10 which this invention is directed are, of course, well known in the art. The truck of my invention contributes to the art certain features of operation and construction which are of exceeding merit, and which I shall first describe generally and then more specifically.

In the truck of my invention, the lifting mechanism comprises a pivoting member operated by the lifting handle of the truck, the pivoting member being carried by the elevating platform. 20 In the preferred embodiment of my invention, this pivoting member takes the form of a ratchet, and it is locked by a pawl relatively to the lifting platform when the pawl is in one position. When actuated thereafter by the lifting handle, 25 it does not pivot relatively to the platform, and therefore the swinging movement of the lifting handle imparts lifting movement to the elevating platform.

Preferably, the means of connection between 30 the lifting handle and the reciprocating ratchet are such that the lifting handle may operate the ratchet in any steering position, so that the lifting handle may function as the steering member for the truck. The means of connection between 35 the lifting handle and the reciprocating ratchet are in themselves novel and form a distinct contribution to the art.

For holding the elevating platform in any elevated position, I employ holding mechanism 40 which is biased by the weight of the elevating platform out of holding position. The control means for this holding mechanism maintains the holding mechanism against movement by the weight of the platform out of holding position. 45 When the control means are moved into release position, the weight of the platform contributes to the movement of the holding mechanism out of holding position in a most novel manner.

In the preferred form of my invention, the 50 holding mechanism takes the form of a toggle which is biased towards collapse, and which is held against collapse by certain control mechanism. My holding mechanism forms an improvement over the holding mechanism which is disclosed in the Stuebing Patent No. 1,785,368, which

patent is owned by The Yale & Towne Manufacturing Company, the owner of this application.

The control for the lifting mechanism whereby the lifting handle may be released for free movement, and the control of the holding mechanism, are interrelated. The purpose of this interrelation is to free the lifting handle relatively to the lifting mechanism prior to the release of the holding mechanism, so as to avoid a flying handle. The means whereby I obtain this result are novel and form an improvement over the means disclosed by Stuebing in the patent mentioned above. 5

As a further feature of my invention, I arrange to connect my lifting handle to the lifting mechanism automatically upon the movement of the lifting platform to its lowered position. Because of this construction, no operation of the control mechanism is required as in prior art trucks, as a prerequisite to the operation of the lifting 20 mechanism. In this way, I eliminate an operation required in prior art trucks; and make it possible for my truck to complete a lifting and lowering cycle in less time than prior art trucks. As a further feature, the lowering of the platform resets also the holding mechanism so that 25 it is in a position thereafter to hold the elevating platform as it is lifted by the movement of the lifting handle.

Still a further feature of the construction is 30 the mounting of the lifting and holding mechanism and the mechanism which checks the lowering movement of the elevating platform, all in very compact relationship, and preferably within a casing, so that a compact and efficient "stream- 35 line" design is obtained.

The features of my truck thus generally described are probably the most important thereof, but other desirable constructions and combinations will appear as I describe my invention in 40 greater detail, and will be claimed as part of my monopoly. Those skilled in the art will readily appreciate that the various features of my invention may be obtained through many different physical embodiments, and I therefore expect to 45 secure for myself a monopoly sufficiently broad to prevent the utilization of my contribution by others in such different physical embodiments.

Referring now more particularly to the drawings, Fig. 1 is an elevation of my lift truck, while 50 Fig. 2 is a view looking downwardly thereon, certain parts of the rear end being shown in section. Fig. 3 is a partial section and elevation through the front end of the truck showing the various parts at the beginning of the lifting op- 55

eration, and before any lifting has been done. Fig. 4 is a section of Fig. 3 taken along lines 4-4 of Fig. 3. Fig. 5 is a view similar to Fig. 3, but showing the elevating platform lifted somewhat 5 from its position of Fig. 3. Fig. 6 shows the parts of Fig. 5, but with the lifting mechanism positioned so that the lifting handle is free for swinging movement without actuating the lifting mechanism. Fig. 7 is a view of certain parts of 10 Fig. 6 showing the holding mechanism released so that the elevating platform may be lowered. Fig. 8 shows the resetting of the holding pawl upon the lowering movement of the lifting platform, with the lifting pawl of the lifting mechanism 15 about to be reset.

Referring now more particularly to the drawings, and especially Figs. 1 and 2, I shall first describe my truck generally. The main frame is designated by reference numeral 18, while the 20 elevating platform is designated by reference numeral 11. At the front end of the elevating platform there is a casing 12 in which is mounted the lifting mechanism and also the holding mechanism. Within the casing 12, there is also 25 mounted a vertical check or dashpot 13, which is best shown in Fig. 4, and which is connected at one end to the shaft 14 of casing 12, and at its other end to the main frame at point 15. The check 13 is preferably of the hydraulic type 30 well known in this art, and cushions the elevating platform as it moves downwardly after being released, all as is understood by those familiar with the art.

The front end of the main frame carries a 35 steering head 16 which includes a pair of steering wheels 17, and a lifting and steering member 18 to which is fixed the lifting and steering handle 19. The construction of the steering head will be described in more detail later in 40 the specification.

The rear end of the truck is supported by a 45 pair of wheels 17a mounted on an axle 17b, as is standard in this art. The main frame 18 extends beyond the axle 17b, and supports upon 50 this extension a shaft 20, which supports through bushings 21, the rear lifting links 22. The links 22 are in turn connected by a reinforcing tube 23a. Welded to the links 22 is a shaft 23 which 55 is mounted relatively to the elevating platform 11 in bearings 24. The construction of this rear end will not be described in more detail here, nor will the purpose of this construction be indicated, since this construction will be made 60 the subject of a separate patent application.

The forward end of the elevating platform 11 is supported in a conventional manner by forward links 25. It will be understood by those skilled in the art that upon operation of the 65 handle 19, the lifting and steering member 18 will be actuated, operating the lifting mechanism within the casing 12 in a manner to be described later, whereby to lift the elevating platform on said forward links 25 and rear links 22 relatively to the main frame.

Now that I have described thus generally my 70 truck, I shall refer to Figs. 3 and 5 for a description of my steering head 16. The steering head 16 may, of course, be of any conventional type, but in my preferred construction, it includes a 75 sleeve 26a which carries the front axle 26 on which are mounted the front steering wheels 17. Suitable thrust bearings 27, 28, 29 accept the various loads of the steering head so that the steering head may be free to rotate and thereby 80 swivel the wheels 17. The upper end of the

steering head 16 supports a shaft 30 on which is mounted for pivoting movement the lifting and steering member 18, to which, as has already been indicated, is secured the lifting and steering handle 19.

Formed integrally with the steering head 16 are a pair of ears 31, to which is pivotally secured a bar 32 which carries on a pin 33 a roller 34 mounted for movement within the hollow handle 19. Extending upwardly from the pin 33 is a guide bar 35, about which is mounted a spring 36. The spring 36 operates between a disk 37 on the guide bar 35 and a pin 38 fixed to the upper part of the handle. It will be readily appreciated that it is the function of the spring 36 to press the handle upwardly into its position of Fig. 3, thus compensating for the weight of the handle. The spring is compressed as the roller 34 enters the handle when the handle swings downwardly, so as to be effective 20 to swing the handle upwardly when it is released. This feature is called a balanced handle, and its construction is covered broadly in a co-pending application.

In the position of the handle of Fig. 3, the 25 surface 39 of the member 18 is adapted to rest against the surface 40 of the steering head 16, thus limiting the upward movement of the handle 19 by balancing spring 36. In this position of the handle, it is readily seen that the 30 truck may be pushed by application of force to the handle, with the forces accepted by the two surfaces 39 and 40. It will, of course, be appreciated that steering movement is imparted to the steering wheels 17 by the handle 19 through 35 the member 18, the shaft 30, and the sleeve portion 26a of the steering head.

For operating the lifting mechanism, the member 18 is equipped with a pin 41 to which is secured a vertical lifting strut 42, as is best shown 40 in Fig. 3. The upper end of the strut 42 enters partially into a bore within a shaft 43, and is thus adapted for rotation in its own axis relatively to the said shaft 43. The shaft 43 is in turn mounted for rotation on a horizontal axis 45 within the ears 44 of what I term a lifting ratchet 46.

A threaded adjusting pin 48 is threaded within a block 47 mounted for rotation with the shaft 43, and extends downwardly into the bore in which 50 lies the upper end of strut 42. The block 47 is also traversed by the upper end of the strut 42, as is shown. Through this construction, pin 48 bears against the upper end of strut 42 for accepting the thrust of the strut 42 as the strut 55 moves upwardly. A further function of the adjusting pin 48 is to follow the downward movement of the lifting strut 42, as the lifting ratchet 46 moves downwardly with the said strut 42. By rotating the pin 48, any play between it and 60 the strut 42 is eliminated.

The lifting ratchet 46 is mounted for rotation about the shaft 14, which is the same shaft to which is secured one end of the hydraulic check previously described by me. For controlling the 65 rotation of the lifting ratchet 46 about the shaft 14, I utilize what I term a lifting pawl 48 which cooperates with the teeth 49 of the lifting ratchet 46. The lifting pawl 48 is supported on a shaft 50 secured to the casing 12 through an internal 70 bearing ear 51 formed within the casing, as is shown in Fig. 4, and through a further bearing on the outer shell of the casing.

Mounted about this same shaft 50 is what I term a pawl carrier 52 which is U-shaped in 75

cross section, and which supports through a shaft 53 the holding pawl 54. Shaft 53 will be termed by me a control shaft, for reasons which will be apparent later. The holding pawl cooperates 5 with a holding ratchet 55 which bears against the main frame at 56, and through its said bearing at 56 is capable of considerable necessary movement. The ratchet 55 is maintained against its bearing 56 by the spring 57, all as is quite apparent from a view of Fig. 3. It will be noted that the ratchet 55 is supported relatively to the casing 12 of the lifting platform by the shaft 53, so that as the lifting platform and the casing 12 move upwardly to the position of Fig. 5 from the position of Fig. 3, the ratchet 55 will remain properly supported. The bearing 56 allows for such changes of position of the ratchet 55 as take place during its movement from Fig. 3 to Fig. 5.

Preferably, a single spring 59 is connected at 20 to the lifting pawl 48, and at 61 to the holding pawl 54, and urges the lifting pawl 48 against the lifting ratchet 45, while simultaneously pressing the teeth 62 of the holding pawl 54 against the teeth 63 of the holding ratchet 55.

25 A further function of the spring 59 is to tend to break the toggle, in effect, formed by the pawl carrier 52 and holding pawl 54, between the following points; the point where the pawl teeth 62 engage the teeth 63 of the holding ratchet 55, the control shaft 53, and the pivot shaft 50. This tendency to break the toggle, in effect, is resisted by control mechanism designated generally by reference numeral 64. This control mechanism 64 is in the form of a three-armed cam splined 30 to a shaft 65, to which shaft is secured also as by splining, or in any other suitable way, the control pedal 66.

One arm of the control mechanism 64 is pinned at 67 to the rod 68 to which is fixed a disk 69. A spring 70 is mounted about the rod 68, with its 40 lower end against disk 69. Spring 70 bears at its upper end against a collar 71 mounted on rod 70 and which is secured through pins 72 to ears extending from lifting ratchet 45. It will be seen that the spring 70 will tend, through the collar 45 71, to rotate the lifting ratchet 45 in a clockwise direction so as to bring the adjusting screw 46 against the upper end of the vertical lifting strut 42, as was previously described, thus taking up any play in the lifting mechanism and assisting the balancing spring 36 to maintain the lifting handle in its vertical position of Fig. 3. Spring 70 causes ratchet 45 to follow the non-lifting movement of strut 42. At its other end, the spring 70 tends to rotate the control mechanism 64 in a counter clockwise direction about the axis of shaft 65.

In the position of the parts in Fig. 3, it will of course be noted that a second arm of the control 60 mechanism 64, designated by reference numeral 73, has a cam surface 74 against which presses a control roller 75 secured about the control shaft 53. In this position of the parts, the collapse of the toggle previously described is prevented, and the holding pawl 54 may be maintained by the spring 59 with its teeth 62 ready to engage the teeth 63 of ratchet 55 as soon as the elevating platform is lifted a slight amount.

With the parts in the position of Fig. 3, a 70 downward swinging movement of the handle 19 will impart vertical movement to the lifting strut 42, which will tend to rotate the lifting ratchet 45 in a counter clockwise direction. This tendency of the lifting ratchet 45 to rotate will, of course, be prevented by the lifting pawl 48, which

locks the ratchet against any clockwise rotation relatively to the elevating platform. Therefore, a vertical swinging movement of the handle 19 will lift the ratchet 45 and the casing 12, and therefore, the elevating platform, from the position of Fig. 3 to the position of Fig. 5. Thereafter, a return of the lifting handle from a downward position to the vertical position of Fig. 5 will be possible, because the teeth 49 of ratchet 45 will simply ratchet past the teeth of the pawl 48, the cooperating teeth of the pawl and ratchet being designed for this purpose. This ratcheting movement is allowed, of course, by the spring 59, which is simply extended, as is understood by those skilled in the art. From the position of Fig. 5, the elevating platform may be further lifted by a second downward swinging movement of the handle 19, just as has already been described.

Referring now again to Fig. 5, it will be noted 20 that the lifting parts are all in practically the same relation as in Fig. 3, except that the pawl 48 is now in contact with different teeth of the lifting ratchet 45, while the teeth 62 of the holding pawl 54 are in contact with holding teeth 25 63 of the ratchet 55. It will be noted, furthermore, that the point of contact between the teeth 62 of pawl 54 and the teeth 63 of ratchet 55 is so related to the control shaft 53 and the shaft 50 upon which is mounted the pawl carrier 52, that 30 the toggle, in effect, formed by the pawl 54 and the pawl carrier 52 has a tendency to be broken, or to be collapsed by the weight of the load platform itself, just as previously described. This tendency to break is, of course, opposed by the 35 cam surface 74 on the control arm 73 of the control mechanism 64, against which bears the roller 15 of control shaft 53.

If, in the position of the parts in Fig. 5, it is decided that the platform has been sufficiently 40 elevated, the operator may release the lifting handle 19 from the lifting mechanism, so that he may pull the truck away by the swinging of the lifting handle 19 down to its position of Fig. 6, in which position the truck may be more easily 45 pulled. In order that this may be done, the control mechanism has a further lever arm 76 adapted to contact a downwardly extending arm 77 of the lifting pawl 48. When the operator of the truck steps on the treadle 68, the shaft 65 will rotate control mechanism 64 clockwise from the position 50 of Fig. 5 to the position of Fig. 6, bringing the arm 76 against the arm 77, and thus moving the lifting pawl 48 away from engagement with the lifting ratchet 45, as is best shown in Fig. 6.

This movement naturally compresses further the spring 70-operating between the control mechanism 64 and the lifting ratchet 45. The return movement of the control mechanism by spring 78 from the position of Fig. 6 to the position of Fig. 5 is resisted by the engagement of the control roller 75 on the control shaft 53 with a further cam surface 78 formed on the control arm 73. This is the relation of the parts in Fig. 6. It will be noted that in this position, the weight 65 of the load on the elevating platform is exerting pressure on the holding pawl 54 tending to break the toggle at the control shaft 53. Thus, the weight of the platform is, in effect, assisting in maintaining the control mechanism in its position of Fig. 6 against its tendency to rotate back to the position of Fig. 5.

If, in the position of the parts in Fig. 6, it is desired to lower the platform, this can be done only by moving the teeth 62 of the holding pawl 75

54 away from teeth 63 of the holding ratchet 55. The manner in which this is done is best shown in Fig. 7 wherein the treadle 66 has been rotated to an extreme position, bringing the cam surface 79 of the control mechanism opposite the control roller 75 of the control shaft 53.

10 In this position of the control mechanism, the weight of the lifting platform imparts an initial movement to the lifting pawl 54 to break the toggle through the control shaft 53. Further movement is contributed by the spring 59, which functions to move the control shaft to the position of Fig. 7 through the action of an extending cam surface 80 formed on the holding pawl 54. The 15 action is as follows:

Immediately upon the rotation of the control mechanism to the position of Fig. 7, the weight of the platform acts against holding pawl 54 to break the toggle at the control shaft 53. The 20 spring 59 then aids in rotating the pawl 54 about the control shaft 53, bringing the cam surface 80 of the holding pawl 54 against the holding ratchet 55. This moves the control shaft 53 and its roller 15 against the cam surface 79 of the release mechanism and holds it there. From this point on, 25 the platform is lowered slowly under the control of the check or dashpot 13.

It will be noted that the cam surface 79 is of a form different from the cam surfaces 74 and 30 78. This is due to the fact that the roller 15 of control shaft 53 is maintained against surfaces 74 and 78 partly by the weight of the platform, whereas in the relation of the parts in Fig. 7, only the spring 59 functions to maintain the roller 35 15 against the cam surface 79. In the position of the parts in Fig. 7, the form of the cam surface 79 will prevent the functioning of the spring 10 which tends always to rotate the control mechanism 64 back to its position of Fig. 3.

40 With the parts in the position of Fig. 7, the elevating platform, including its casing portion 12, moves downwardly towards the position of Fig. 8. As it does so, an adjustable resetting screw 81, suitably secured through a connecting bar 82 to the pawl carrier 52, moves against the 45 upper end surface 83 of the holding ratchet 55. In so doing, it tends, of course, to re-align the toggle, in effect, formed by the pawl carrier 52 and the holding pawl 54, thus carrying the control roller 75 out of the depression of the control 50 mechanism formed by cam surface 79.

A very slight movement beyond that of Fig. 8, through the further lowering of the platform, will bring the teeth 62 of the holding pawl 54 just below the first of the teeth 63 of the holding ratchet 55, and will further straighten the toggle through the control shaft 53. This is the position of these 55 particular parts in Fig. 3. This movement will also bring the control roller 75 entirely out of the depression formed by cam surface 79, allowing 60 free rotation of the control mechanism 63 by the spring 10 back to its position of Fig. 3.

This rotation of the control mechanism by spring 10 will bring the cam surface 74 of the control arm 73 against the control roller 75, thus 65 reestablishing the control mechanism to its control position of Fig. 3. At the same time, the lever arm 76 of the control mechanism will be withdrawn from contact with the downwardly depending arm 77 of the lifting pawl 48, releasing 70 the pawl 48 for movement back into engagement with the teeth 49 of the lifting ratchet 45. The parts will now be restored for a second lifting and lowering cycle.

75 While the description above given of the operating structure is probably quite sufficient for

an understanding thereof, I shall, for the sake of clarity, review a complete lifting and lowering operation once again.

Starting from the position of Fig. 3, the downward swinging movement of the handle 19 acts 5 through lifting strut 42 to move the lifting ratchet 45 and the casing 12 of the elevating platform 11 upwardly due to the fact that the lifting ratchet 45 cannot rotate because of the lifting pawl 48. This upward movement of the 10 elevating platform causes the teeth 62 of the holding pawl 54 to ratchet upwardly relatively to the teeth 63 of the holding ratchet 55, to the position of Fig. 5, wherein the lifting platform is maintained in a particular elevated position. 15 The lifting handle, which has been swung downwardly to perform the lifting operation, may now be swung upwardly to restore it to the position of Fig. 5, through the ratcheting action of the teeth of the lifting pawl 48 and the teeth 49 of 20 the lifting ratchet 45. From this point, a further downward swinging movement of the handle 19 will further lift the elevating platform.

If, in the position of the parts in Fig. 5, it is desired to release the lifting mechanism so that 25 the lifting handle may be swung downwardly to the position of Fig. 6 to pull the truck, the operator need merely step on the treadle 66, rotating the control mechanism 64 to bring the arm 76 against the downwardly depending arm 77 of the 30 lifting pawl 48, thus moving the pawl 48 to the position of Fig. 6 against the resistance of the spring 59. The control mechanism will be maintained in this position due to the coaction of the control roller 74 with the depression of the cam surface 78, the control roller being held in this 35 position by the combined force of the spring 59 and the weight of the platform, the weight of the platform tending to break the toggle, in effect, formed about control shaft 53 through pawl 40 carrier 52 and pawl 54.

If, with the parts in the position of Fig. 6, it now be desired to lower the load, the operator steps on the treadle 66 once again, rotating it to the position of Fig. 7, in which position the 45 toggle, in effect, about the shaft 53 is completely broken, first by the load and then by the spring 59. The deep depression formed by the cam surface 79 cooperates with the control roller 75 to hold the control mechanism in its position of Fig. 7 against the force of the spring 10, which 50 tends always to rotate it back into its initial position of Fig. 3.

As the lifting platform is lowered from its position of Fig. 7 to the position of Fig. 8, the adjustable resetting screw 81 contacts the upper end of the holding ratchet 55, thus tending to restore the toggle, in effect, formed between the pawl carrier 52 and the holding pawl 54, and bringing the control roller 74 from the relatively 60 deep depression 79 of the control mechanism. The spring 10 then rotates the release mechanism back to the position of Fig. 3, just as the control roller 75 is moved slightly beyond the position of Fig. 8 by the further lowering of the platform. 65 This restores the holding pawl 54 to holding relation relatively to the ratchet 55, and withdraws the lever arm 76 from contact with the downwardly depending arm 74 of the lifting pawl 48, thus restoring the lifting pawl to normal lifting position. Downward swinging movement of the handle at this time without any further operation by the operator of the truck 70 will elevate the platform.

I now claim:

1. In a truck of the class described, a main 75

frame, an elevating platform, a lifting ratchet mounted for rotation on a pivot fixed relatively to said platform, a lifting handle, means whereby predetermined movement of said lifting handle rotates said ratchet on its pivot, and means for locking said ratchet against rotation by said predetermined handle movement whereby the said movement of said lifting handle moves said ratchet and platform upwardly as a unit relatively to said main frame.

2. In a truck of the class described, a main frame, an elevating platform, a lifting ratchet mounted for rotation on a pivot fixed relatively to said platform, a lifting handle, means whereby movement of said lifting handle rotates said ratchet on its pivot, and a lifting pawl on said platform for locking said ratchet against rotation by said handle in one direction about said pivot, while allowing free rotation in a reverse direction, whereby movement of said handle in one direction moves said ratchet and platform upwardly, while a reverse movement of said handle thereafter moves said ratchet relatively to said pawl and platform to a position from which a second movement of said handle imparts further lift to said ratchet and platform.

3. In a truck of the class described, a main frame, an elevating platform, a lifting ratchet mounted for rotation on a pivot fixed relatively to said platform, a lifting handle pivoted on said main frame and adapted for vertical swinging movement, means connecting said handle and lifting ratchet for rotating said ratchet back and forth on its pivot as said handle swings upwardly and downwardly on its pivot, a lifting pawl mounted on said platform for locking said ratchet against rotation on its pivot as said handle swings downwardly, while allowing free rotation of said ratchet when said handle swings upwardly, whereby downward swinging of said handle moves said ratchet and platform upwardly, while upward swinging of said handle thereafter moves said ratchet on its pivot and relatively to said pawl to a position from which a second downward swinging of said handle will impart further lift to said platform through said ratchet.

4. In a truck of the class described, a main frame, an elevating platform, a lifting ratchet mounted for rotation on a pivot fixed relatively to said platform, a lifting handle pivoted on said main frame and adapted for vertical swinging movement, means connecting said handle and lifting ratchet for rotating said ratchet back and forth on its pivot as said handle swings upwardly and downwardly on its pivot, a lifting pawl mounted on said platform for locking said ratchet against rotation on its pivot as said handle swings downwardly, while allowing free rotation of said ratchet when said handle swings upwardly, whereby downward swinging of said handle moves said ratchet and platform upwardly, while upward swinging of said handle thereafter moves said ratchet on its pivot to a position from which a second downward swinging of said handle will impart further lift to said platform through said ratchet, and holding mechanism for holding said platform in each position to which it is elevated by said handle and lifting ratchet.

5. In a truck of the class described, a main frame, an elevating platform, a lifting ratchet mounted for rotation on a pivot fixed relatively to said platform, a lifting handle pivoted on said main frame and adapted for vertical swinging movement, means connecting said handle and

lifting ratchet for rotating said ratchet back and forth on its pivot as said handle swings upwardly and downwardly on its pivot, a lifting pawl mounted on said platform for locking said ratchet against rotation on its pivot as said handle swings downwardly, while allowing free rotation of said ratchet when said handle swings upwardly, whereby downward swinging of said handle moves said ratchet and platform upwardly, while upward swinging of said handle thereafter moves said ratchet on its pivot to a position from which a second downward swinging of said handle will impart further lift to said platform through said ratchet, holding mechanism for holding said platform in each position to which it is elevated by said handle and lifting ratchet, and release mechanism for moving said lifting pawl from said lifting ratchet and thereafter releasing said holding mechanism to allow lowering of the platform.

6. In a truck of the class described, a main frame, an elevating platform, a lifting ratchet mounted for rotation on a pivot fixed relatively to said platform, a steering head on said main frame, a lifting handle mounted for swinging movement on said steering head while adapted to impart steering movement thereto, means whereby downward swinging movement of said lifting handle in any steering position thereof rotates said ratchet on its pivot, and means for locking said ratchet against rotation whereby the said movement of said lifting handle moves said ratchet and platform upwardly as a unit.

7. In a truck of the class described, a main frame, an elevating platform, a lifting ratchet mounted for rotation on a pivot fixed relatively to said platform, a steering head on said main frame, a lifting handle mounted for swinging movement on said steering head while adapted to impart steering movement thereto, universal means of connection between said lifting handle and ratchet whereby downward swinging movement of said handle in any steering position thereof rotates said ratchet on its pivot, a lifting pawl mounted on said platform for locking said ratchet against rotation on its pivot as said handle swings downwardly, while allowing free rotation of said ratchet when said handle swings upwardly, whereby downward swinging of said handle moves said ratchet and platform upwardly, while upward swinging of said handle thereafter moves said ratchet on its pivot to a position from which a second downward swinging of said handle will impart further lift to said platform through said ratchet.

8. In a truck of the class described, a main frame, an elevating platform, a lifting ratchet mounted for rotation on a pivot fixed relatively to said platform, a lifting handle, means whereby movement of said lifting handle rotates said ratchet on its pivot, means for locking said ratchet against rotation whereby the said movement of said lifting handle moves said ratchet and platform upwardly as a unit, means for releasing said ratchet from said locking means for free rotation in a lifted position of said platform whereby to free said handle, and means for moving said locking means back into ratchet locking position actuated by movement of said lifting platform to a lowered position.

9. In a truck of the class described, a main frame, an elevating platform, a lifting ratchet mounted for rotation on a pivot fixed relatively to said platform, a lifting handle pivoted on said main frame and adapted for vertical swinging movement, means connecting said handle and

lifting ratchet whereby to rotate said ratchet back and forth on its pivot as said handle swings upwardly and downwardly on its pivot, a lifting pawl mounted on said platform for locking said 5 ratchet against rotation on its pivot as said handle swings downwardly, while allowing free rotation of said ratchet when said handle swings upwardly, whereby downward swinging of said handle moves said ratchet and platform upward- 10 ly, while upward swinging of said handle thereafter moves said ratchet on its pivot to a position from which a second downward swinging of said handle will impart further lift to said platform through said ratchet, a release mechanism for 15 separating said lifting pawl and ratchet to release the ratchet from the handle in an elevated position of said platform, and means for moving said lifting pawl and ratchet together actuated by movement of said platform thereafter to a 20 lowered position.

10. In a lift truck of the class described, a main frame, an elevating platform, lifting mechanism for lifting said platform relatively to said main frame, a pivoted lifting handle for actuating said lifting mechanism to lift said platform upon downward swinging movement of said handle, means operated in an elevated position of said platform for positioning at least one part of said lifting mechanism so that vertical swinging 25 of said lifting handle thereafter will no longer actuate said lifting mechanism to lift said platform, thereby freeing said handle, and means for restoring said part of said lifting mechanism to lifting position actuated by movement of said 30 platform thereafter to a lowered position.

11. In a lift truck of the class described, a main frame, an elevating platform, lifting mechanism of the pawl and ratchet type for lifting said platform relatively to said main frame, a pivoted 40 lifting handle for actuating said lifting mechanism to lift said platform upon downward swinging movement of said handle, means operated in an elevated position of said platform for positioning at least one part of said pawl and ratchet 45 lifting mechanism so that vertical swinging of said lifting handle thereafter will no longer actuate said lifting mechanism to lift said platform, thereby freeing said handle, and means for restoring said part of said lifting mechanism to lifting position actuated by movement of said 50 platform thereafter to a lowered position.

12. In a lift truck of the class described, a main frame, an elevating platform, lifting mechanism for lifting said platform relatively to said 55 main frame, a pivoted lifting handle for actuating said lifting mechanism to lift said platform upon downward swinging movement of said handle, holding mechanism for holding said platform in any elevated position thereof, means operated 60 in an elevated position of said platform for positioning at least one part of said lifting mechanism so that vertical swinging of said lifting handle thereafter will no longer actuate said lifting mechanism to lift said platform, thereby freeing 65 said handle, said means thereafter actuating said holding mechanism to allow lowering of the platform, and means for restoring said part of said lifting mechanism to lifting position and said holding mechanism to holding position actuated by movement of said platform thereafter to a lowered position.

13. In a lift truck of the class described, a main frame, an elevating platform, lifting mechanism for lifting said platform relatively to said 70 main frame, a pivoted lifting handle for actu-

ating said lifting mechanism to lift said platform upon downward swinging movement of said handle, holding mechanism for holding said platform in any elevated position thereof, means operated in an elevated position of said platform for positioning at least one part of said lifting mechanism so that vertical swinging of said lifting handle thereafter will no longer actuate said lifting mechanism to lift said platform, thereby 5 freeing said handle, means whereby said means thereafter actuating said holding mechanism to allow lowering of the platform, and means for restoring said part of said lifting mechanism to lifting position and said holding mechanism to holding position actuated by movement of said platform thereafter to a lowered position, said holding mechanism being restored to its holding position prior to the restoring of said lifting mechanism to its normal position.

14. In a truck of the class described, an elevating platform, a main frame, means whereby said platform is elevated relatively to said main frame, a pair of hinged levers adapted to hold said platform elevated when it has been elevated to a particular position, means whereby said levers are biased for relative pivotal movement about their hinge and out of holding position, and manually operated means for maintaining said levers against said pivotal movement.

15. In a truck of the class described, an elevating platform, a main frame, means whereby said platform is elevated relatively to said main frame, a toggle mechanism adapted to hold said platform elevated when it has been elevated to a particular position, means whereby said toggle 35 mechanism is biased towards collapse and out of holding relation to said platform, and manually operated means for maintaining said toggle mechanism against said collapse.

16. In a truck of the class described, an elevating platform, a main frame, means whereby said platform is elevated relatively to said main frame, a toggle mechanism adapted to hold said platform elevated when it has been elevated to a particular position, means whereby said toggle 40 mechanism is biased towards collapse and out of holding relation to said platform by the weight of said platform, and manually operated means for maintaining said toggle mechanism against 45 collapse.

17. In a truck of the class described, a main frame, an elevating platform, a lever pivoted to said platform at one end, a control shaft whereby said lever is pivoted to a holding pawl at its other end, a ratchet cooperable with said pawl 55 for locking said platform in any elevated position, said ratchet interlocking with said pawl at a point so related to said control shaft and the pivot point of said lever on said platform whereby the weight of said platform tends to move said 60 control shaft in a direction carrying the pawl away from the ratchet, and a pedal controlled cam for holding said cam shaft against said movement, and movable by said pedal to release said shaft for movement.

18. In a truck of the class described, a main frame, an elevating platform, a lever pivoted to said platform at one end, a control shaft whereby said lever is pivoted to a holding pawl at its other end, a ratchet cooperable with said pawl 70 for locking said platform in any elevated position, a spring for rotating said pawl on said control shaft and against said ratchet, said spring allowing movement of said pawl relatively to said ratchet during the lifting of said plat- 75

form while preventing reverse movement of said pawl and platform, said ratchet interlocking with said pawl at a point so related to said control shaft and the pivot point of said lever on 5 said platform whereby the weight of said platform tends to move said control shaft in a direction carrying the pawl away from the ratchet, and a pedal controlled cam for holding said cam shaft against said movement, and movable by 10 said pedal to release said shaft for movement.

19. In a truck of the class described, a main frame, an elevating platform, a lever pivoted to 15 said platform at one end, a control shaft whereby said lever is pivoted to a holding pawl at its other end, a ratchet cooperable with said pawl for locking said platform in any elevated position, a spring for rotating said pawl on said control shaft and against said ratchet, said spring allowing movement of said pawl relatively 20 to said ratchet during the lifting of said platform, while preventing reverse movement of said pawl and platform, said ratchet interlocking with said pawl at a point so related to said control shaft and the pivot point of said lever on 25 said platform whereby the weight of said platform tends to move said control shaft in a direction carrying the pawl away from the ratchet, a pedal controlled cam for holding said cam shaft against said movement, and movable by 30 said pedal to release said shaft for movement, a lifting mechanism for said truck including a lifting pawl pivoted to said elevating platform, said holding pawl spring acting also on said lifting pawl to urge it into a lifting position, and means whereby said pedal controlled cam moves 35 said lifting pawl out of lifting position and releases said control shaft for moving said holding pawl out of holding position.

20. In a truck of the class described, a main frame, an elevating platform, a lifting ratchet pivoted on said platform, a vertically swinging lifting handle pivoted on said main frame and connected to said ratchet to rotate said ratchet 40 on its pivot when said ratchet is free to rotate or to lift said ratchet and platform as a unit when said ratchet is locked against rotation, a lifting pawl for locking said ratchet against rotation during the swinging movement of said handle in a lifting direction, a holding ratchet, 45 a pawl carrier pivoted on said platform, a holding pawl pivoted on said pawl carrier and cooperable with said holding ratchet to hold said platform in any position to which it is lifted by said lifting handle, means pressing said holding pawl and said lifting pawl against their respective ratchets, the said holding ratchet engaging the holding pawl at a point so related to the 50 pivots of the pawl carrier that said pawl carrier is biased for movement to carry said holding pawl away from holding position, a cam member cooperable with said lifting pawl and said pawl carrier when moved to release position for moving said lifting pawl away from its ratchet and 55 releasing said pawl carrier for movement carrying said holding pawl away from said holding ratchet, a spring pressing said cam away from said release position, said pawl carrier locking said cam in said release position when said pawl carrier is moved to its last named position, and means operated by movement of said elevating frame to a lowered position for moving said pawl carrier so as to reengage said holding pawl and 60 ratchet, and thereby release said cam for movement under said spring pressure into position to 65

release said lifting pawl for movement into engagement with its ratchet.

21. In a truck of the class described, a main frame, an elevating platform, a lifting ratchet pivoted on said platform, a vertically swinging lifting handle pivoted on said main frame and connected to said ratchet to rotate said ratchet on its pivot when said ratchet is free to rotate or to lift said ratchet and platform as a unit when said ratchet is locked against rotation, a 10 lifting pawl for locking said ratchet against rotation during the swinging movement of said handle in a lifting direction, a holding ratchet, a pawl carrier pivoted on said platform, a holding pawl pivoted on said pawl carrier and cooperable with said holding ratchet to hold said platform in any position to which it is lifted by 15 said lifting handle, means pressing said holding pawl and said lifting pawl against their respective ratchets, the said holding ratchet engaging 20 the holding pawl at a point so related to the pivots of the pawl carrier that said pawl carrier is biased for movement to carry said holding pawl away from holding position, a cam member cooperable with said lifting pawl and said pawl 25 carrier when moved to release position for moving said lifting pawl away from its ratchet and releasing said pawl carrier for movement carrying said holding pawl away from holding ratchet, a spring pressing said cam away from 30 said release position, said pawl carrier locking said cam in said release position when said pawl carrier is moved to its last named position, and means operated by movement of said elevating frame to a lowered position for moving said pawl 35 carrier so as to reengage said holding pawl and ratchet, and thereby to release said cam for movement under said spring pressure into position to release said lifting pawl for movement into engagement with its ratchet, means whereby 40 said spring pressing against said cam presses also against said ratchet, and a lifting handle connected to said ratchet against which said ratchet is urged by said spring.

22. In a truck of the class described, a holding 45 ratchet, a holding pawl engaging said ratchet and normally held in engagement with said ratchet, a cam, means whereby said cam locks said pawl against movement out of ratchet engaging position when said cam is in an initial position, said 50 cam being movable from said initial position into a second position in which said pawl is released from said ratchet, a spring pressing against said cam to move it back to its initial position, means locking said cam against movement to said initial 55 position while said pawl is held away from said ratchet, and means for moving said pawl back into engagement with said ratchet actuated by movement of said platform to a lowered position, thereby releasing said cam for movement back to 60 its initial and pawl locking position.

23. In a truck of the class described, a holding 65 ratchet, a holding pawl engaging said ratchet and normally held in engagement with said ratchet, a cam, means whereby said cam locks said pawl against movement out of ratchet engaging position when said cam is in an initial position, said 70 cam being movable from said initial position into a second position in which said pawl is released from said ratchet, a spring pressing against said cam to move it back to its initial position, means locking said cam against movement to said initial position while said pawl is held away from said ratchet, and means for moving said pawl back into engagement with said ratchet when said 75

platform is in a lowered position, thereby releasing said cam for movement back to its initial and pawl locking position.

24. In a truck of the class described, a holding ratchet, a holding pawl engaging said ratchet, a control cam, means whereby said cam locks said pawl in engagement with said ratchet when said cam is in its initial position, a spring pressing said cam into its initial position, means for moving said cam into a second position, means whereby said pawl is separated from its ratchet through movement of said cam to its second position, means locking said cam against movement by its spring back to its initial position while said pawl is separated from its ratchet, and means for moving said pawl into engagement with said ratchet actuated by movement of said platform to a lowered position, thereby releasing said cam for movement back to its initial and pawl locking position.

25. In a truck of the class described, a holding ratchet, a holding pawl engaging said ratchet and normally held out of engagement with said ratchet, a pedal controlled cam, means whereby said cam locks said pawl against movement out of ratchet engaging position while said cam is in an initial position, said cam being movable from said initial position into a second position in which said pawl is released from said ratchet, a spring pressing against said cam to move it back to its initial position, means locking said cam against movement to said initial position while said pawl is held away from said ratchet, and means for moving said pawl into engagement with said ratchet actuated by movement of said platform to a lowered position, thereby releasing said cam for movement back to its initial and pawl locking position, a lifting pawl through which said truck platform is elevated, means whereby said pawl is moved by said cam to non-elevating position as said cam moves to release said holding pawl from its ratchet, the return of said cam by its spring to its initial position releasing said lifting pawl for movement to lifting position.

26. In a truck of the class described, a holding ratchet, a holding pawl engaging said ratchet, a control cam, means whereby said cam locks said pawl in engagement with said ratchet when said pawl is in its initial position, a spring pressing said cam into its initial position, means for moving said cam into a second position, means whereby said pawl is separated from its ratchet upon

movement of said cam to said second position, means locking said cam against movement by its spring back into its initial position while said pawl is separated from its ratchet, and means for moving said pawl into engagement with said ratchet actuated by movement of said platform to a lowered position, thereby releasing said cam for movement back to its initial and pawl locking position, a lifting pawl through which said truck platform is elevated, means whereby said pawl is moved by said cam to non-lifting position as said cam moves to release said holding pawl from its ratchet, the return of said cam by its spring to its initial position releasing said lifting pawl for movement to lifting position.

27. In a truck of the class described, a main frame, an elevating platform, a holding ratchet, a pivoted pawl carrier, a pawl pivoted on said pawl carrier and having a tooth for engaging said ratchet to hold said elevating platform in a lifted position, said pawl having a cam surface extending beyond the tooth thereof, a spring pressing said pawl against said ratchet, means whereby said pivoted pawl carrier is movable on its pivot into a holding position and into a release position, the said pawl being movable with said carrier so that the tooth portion of said pawl is pressed by said spring against said ratchet in the holding position of said carrier while in the release position of said carrier the cam portion of said pawl is pressed against said ratchet and the tooth portion is positioned away from said ratchet.

28. In a truck of the class described, a main frame, an elevating platform, a vertical casing forming part of the front end of said elevating platform, a lifting member mounted on a shaft extending transversely through said casing, a portion of said member extending outwardly of said casing for operation, a hydraulic dashpot check in said casing and secured at its upper end near the upper end of said casing and at its lower end to said main frame, a holding device within said casing and cooperable with holding means extending into said casing from the main frame, a foot treadle outwardly of said casing secured to a shaft supported on said casing for rotation within the casing, and control means for said lifting member and holding device secured on said shaft within said casing and movable by said pedal.

GEORGE QUAYLE.
